DESIGN FOR A SLIPPER

Emile Debusschere, Ardoye, Belgium, assignor to Henri Bendel, Inc., New York, N. Y., a corporation of New York

Application August 30, 1939, Serial No. 86,947

Term of patent 3½ years

To all whom it may concern:

Be it known that I, Emile Debusschere, a citizen of Belgium, residing at Ardoye, Belgium, have invented a new, original, and ornamental Design for a Slipper, of which the following is a specification, reference being had to the accompanying drawing, forming part thereof.

In said drawing:

Fig. 1 is a perspective view of a slipper embodying my new design; and

Fig. 2 is a top plan view of the slipper.

I claim:

The ornamental design for a slipper, as shown.

EMILE DEBUSSCHERE.
